CAN-CLOSING MACHINE

John M. Hothersall, Brooklyn, N. Y., and August E. Almgren, Hillside, N. J., assignors to American Can Company, New York, N. Y., a corporation of New Jersey

Application July 21, 1937, Serial No. 154,926

7 Claims. (Cl. 226—81)

The present invention relates to can closing machines and has particular reference to a machine for closing the flap or attached closure element of a filled fibre milk container, can or bottle and also for reforming the same after closing to seal it against accidental displacement.

An object of the invention is the provision of a can closing machine for sealing filled fibre milk cans or bottles of the type having hinged closure elements or flaps which are preferably attached to the can and which are adapted to be inserted in part into and to close a filling and dispensing opening provided in a wall of the can, the machine also sealing the closure element in can closing position.

Another object is the provision in such a machine of devices for extruding or expanding the closure element after it is in place in its filling and dispensing opening in order to lock the closure element in can sealing position and against accidental displacement during shipment and storage.

Another object is the provision in a machine of this character of members for properly locating and for holding a filled can while its closure element is being expanded in can sealing position.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a can closing machine embodying the instant invention, parts being broken way and other parts broken back and shown in section;

Fig. 2 is a top plan view of the machine, with parts broken away;

Fig. 3 is a fragmentary section taken substantially along the horizontal line 3—3 in Fig. 1;

Fig. 4 is a fragmentary elevational detail of Fig. 2 as viewed from a vertical plane indicated substantially by the line 4—4 in that figure and showing the upper end of a can being operated on;

Fig. 5 is an enlarged vertical section taken substantially along the line 5—5 in Fig. 2, with parts broken away, the view also showing a can having its upper end broken back and shown in section;

Fig. 6 is an enlarged section taken substantially along the horizontal line 6—6 in Fig. 1;

Fig. 7 is a fragmentary top plan as viewed from

a horizontal plane indicated substantially by the line 7—7 in Fig. 5;

Fig. 8 is a sectional detail taken substantially along the line 8—8 in Fig. 7;

Fig. 9 is an elevational detail as viewed from a vertical plane indicated substantially by the line 9—9 in Fig. 7;

Fig. 10 is a bottom plan of an expanding head part of the machine as viewed from a horizontal plane indicated substantially by the line 10—10 in Fig. 5;

Fig. 11 is a view similar to Fig. 10 and showing the movable parts of the head in a different position;

Figs. 12 and 13 are perspective views of two of the moving parts of the head shown in Figs. 10 and 11, Fig. 12 showing one part as viewed from one end while Fig. 13 shows the other part as viewed from the opposite end; and

Fig. 14 is an enlarged fragmentary section of an expanding head and one corner of a can being operated on, the view being taken substantially along the line 14—14 in Fig. 2.

An exemplary form of can which is adapted to be closed in the machine illustrated in the drawings is fully disclosed in the Hothersall Patent No. 2,085,979, issued by the United States Patent Office on July 6, 1937. Such a can is herein indicated by the letter *b* (Figs. 2, 4 and 5). The can is preferably made of fibre board and is provided with fibre top and bottom end members. The top end member is formed with a filling and dispensing opening *c* which is disposed at one corner of the can. This opening is adapted to be closed and sealed, after the can is filled, by a flap or closure element *d* which is hingedly secured to the top end member. The closure element is provided with a plug section *e* formed to fit into and fill the opening *c* when the closure element is in can closing position.

As a preferred embodiment of the present invention the drawings disclose a can closing machine in which the cans, filled with their contents and ready to be finally sealed, are received from a suitable can filling machine A (Fig. 2) or other can handling device. The cans are in vertical position with their closure elements *d* open so as to uncover their filling openings *c*.

A received can *b* is first passed through flap closing devices *B* where its upright closure element *d* is pushed down flat so that the plug section *e* will enter and completely fill the filling opening *c*. During this operation the can is steadily advanced toward a flap sealing mechanism C.

While in the mechanism C the closed can is advanced along a curved path of travel in time with a sealing head D which is moved down into engagement with the top of the moving can. 5 Such a head may be of the type disclosed in the Hothersall Patent No. 1,823,047, issued by the United States Patent Office on September 15, 1931. Parts of the sealing head D enter the closed plug section e and extrude its side walls, 10 expanding them to form an outwardly projecting bead f as shown in Fig. 14. The expanded bead is larger in diameter than the opening c and it therefore extends under the top end member adjacent the edges of the opening. The bead thus locks the closure element d in can sealing 15 position against accidental opening.

After sealing, the can is removed from the machine by discharge instrumentalities E. In this removal provision is made for carrying the 20 closed and sealed can along a straight path of travel to permit inspection.

The filled cans b move in a continuous procession from the time they are first received from the filling machine A. The cans enter pockets 21 25 (Fig. 2) of a can feeding turret 22 of the flap closing devices B. The turret is mounted on the upper end of a vertical shaft 23 which is journaled in a bearing 24 (see also Fig. 1) formed on a main machine frame 25. At its lower end the shaft 23 30 carries a spur gear 26 (see also Fig. 3) which is formed integrally with a bevel gear 27. The bevel gear 27 meshes with a driving pinion 28 mounted on a main drive shaft 29 journaled in a bearing 31 formed in a side of the main frame 25. The 35 main drive shaft is continuously rotated in any suitable manner and hence through the gear connection just described revolves the turret 22.

Rotation of the turret 22 advances the cans b 40 through a curved path of travel. During this advancement the cans are supported on and are moved across a flat table 35 which is located under the turret and which is secured to a flange 36 formed on the bevel gear shaft bearing 24. The cans are retained in the turret pockets 21 by 45 inner and outer curved guide rails 37, 38 which are bolted to the top of table 35.

A flap closing member or bar 39 having an upturned end 41 (see Figs. 2 and 4) is disposed over 50 the top of the path of travel of the cans b for closing the can flap or closure elements d as hereinbefore described. This bar also holds the flap d closed while the can is advanced. The bar is bolted to an upright 42 formed on the side of the outer curved guide rail 38.

The flap sealing mechanism C is located adjacent the flap closing devices B and when the advancing closed cans reach the end of the flap closing bar 39 they are then advanced by other feeding means. The closed cans are transferred 60 by the inner guide rail 37 from the pockets 21 of the feeding turret 22 into spaced pockets 45 (Figs. 2, 5 and 7) of upper and lower turret members which form a duplex or double can sealing turret 46 which is rotated in time with the can feeding turret 22.

The can sealing turret 46 is keyed to a rotatable column 48 (Figs. 1 and 5) which is supported on a base 49 formed in the main frame 25. The column surrounds a stationary central post 51 the lower end of which is carried in a bore 52 formed in the base 49. The post is held in the base by a key 53. The column is rotated around the post by a gear 54 (see also Fig. 3) which is formed integrally with the column and which is driven by the spur gear 26 hereinbefore mentioned.

The column 48 also carries a can supporting disc 56 (Figs. 5 and 7) which is disposed under the turret 46 and which rotates with the column. The top of the disc is flush with the top of the table 35 and insures easy transfer of the cans. 5 The disc is provided with a plurality of clearance recesses 57, each of which contains a flat yieldable pad 58. There is one of these pads located directly under each pocket 45 of the turret 46 and when a closed can b moves from the turret 22 to the turret 46 it passes onto one of the pads and 10 remains so located while in the turret pocket.

Each pad 58 is provided with a depending shouldered stem 61 which is carried in a shouldered bore 62 formed in a boss 63 on the bottom of the disc 56. A coiled compression spring 64 surrounds the stem and is interposed between the shoulders of the stem and the bore. This spring supports the pad and permits the latter to be depressed slightly in its clearance recess when occasion requires. A collar 65, pinned to the outer end of the stem limits the upward movement of the pad under the action of the spring and normally holds the top of the pad flush with the top of the disc 56. 15

The closed cans b are held against displacement in the pockets 45 of the rotating turret 46 by a guide rail 66 which forms a continuation of the inner guide rail 37. The cans are also held by cam operated clamping arms 67 (Figs. 5, 7, 8 20 and 9) which are moved into position against the outer corner of a transferred can as soon as it is received in its pocket 45. The upper end of each of the arms is formed with a clamping plate 68 which is shaped to fit the square contour of the 25 can.

Each clamping arm 67 is mounted on a pivot pin 69 which is carried in a bearing 71 formed on the bottom of the can supporting disc 56. A gear 72 is also mounted on the pivot pin and 40 meshes with a rack formed in the top of a horizontal slide 73. The slide is retained in slide-ways formed in lugs 74 which depend from the bottom of the disc 56 and which are located adjacent the pin bearing 71. The slide carries a 45 cam roller 75 which operates in a cam groove 76 (see also Fig. 6) formed in a stationary cam 77 bolted to an annular boss 78 (see also Fig. 1) formed on the top of the main frame 25.

As the rotating column carries the turret 46 50 and can supporting disc 56 around the stationary cam 77, the rollers 75 and slides 73 swing the can clamping arms 67 into can holding position in time with the reception of the cans b in the turret pockets 45. It is while the cans b are so held 55 in their pockets that their closed closure elements d are sealed by the flap sealing heads D.

There is one sealing head D for each pocket 45 of the turret 46, each head being located directly over the top of the filling opening c of the 60 cans b retained in its pocket. These heads are carried in a head block 81 (Figs. 1, 2 and 5) which is keyed to the upper end of the column 48 and which therefore rotates with the column.

Each sealing head D includes a head body 82 65 (Figs. 1, 2 and 14) having an upright hollow stem 83 which fits within a vertically movable sleeve section 84 of a cam slide member 85 carried in a bore 86 formed in the head block 81. The head D is supported on a rod 87 which extends down through the middle of the sleeve section 84 and the head body stem 83, the lower end of the rod having a shouldered portion 88 which engages with a shoulder 89 formed on the inside of the head body stem. The upper end of the 75

rod is threaded into the upper end of the cam slide 85 and is locked in place by a setscrew 80 which is threaded into the cam slide. A compression spring 91 surrounds the rod and is interposed between the cam slide 85 and the top of the head body stem 83 and provides a yieldable connection between these parts.

At its upper end the cam slide 85 carries a cam roller 95 which operates in a cam groove 96 formed in a stationary cam 97. The cam is keyed onto the upper end of the stationary post 51. Side wings 98 (Figs. 1 and 2) formed on the cam slide engage against the outer surface of the cam and prevent turning of the slide in the head block 81.

As the column 48 rotates around the post 51 it carries the cam rollers 95 around in the groove 96 of the cam 97 and hence reciprocates the cam slide 85 in the head block 81. It is this action which brings the sealing heads D down into flap sealing position on top of the advancing cans b.

Sealing of the closed flaps d is effected by articulate shaped expanding die members 101, 102 (Figs. 5, 10, 11, 12, 13 and 14) which are associated with each sealing head D. Each die member is formed on the inner end of a slide bar 103 which operates within a groove 104. The grooves 104 are radially disposed in the bottom of each head body 82. The slide bars are held in place by a bottom plate 105 which is secured by screws 106 to the bottom of the head. An endless coil spring 108 extends around the sealing head and is retained in curved seats 109 which are formed in the outer ends of the radially disposed slide bars 103. This spring normally holds the slide bars in toward the center of the head and in a contracted position as best shown in Fig. 10.

When a sealing head D is brought down on top of a closed can b by the cam 97 and cam slide 85, the bottom plate 105 of the head presses the can or bottle down in its turret pocket 45 against the resistance of the yieldable can supporting pad 58 until the top end of the can adjacent its end seam is pressed firmly against the edge of the pocket and clamped between the upper turret wall 46 and the sealing head (Fig. 14). The pocket is undercut as at 111 (Fig. 14) for this holding purpose. This action lowers the contracted die members 101, 102 into the plug section e of the closure element d.

Proper vertical location of the die members with respect to the plug section e is effected by the bottom plate holding screws 106. These screws extend down below the plate and serve as stops engaging against the top of the turret 46 and arresting further downward movement of the head D. However, the cam 97 continues to depress the cam slide 85 against the resistance of its spring 91.

This continued movement of the cam slide pushes the head supporting rod 87 down within the head body stem 83 and presses the extreme lower end of the rod against the inner faces of the radially disposed die members 101. The end of the rod and also the inner faces of the die members are provided with corresponding tapered surfaces which cooperate to effect an outward or expanding movement of these die members. The expanding die members 101 slide along the inner faces of the die members 102 and hence effect a similar expanding movement of the latter. Thus all the die members 101, 102 and the slide bars are simultaneously expanded against the resistance of the endless spring 108.

The die members 101, 102 are thus pressed out-

wardly against the side walls of the plug section e of the closure element d, and form a complete and full circle as shown in Fig. 11. It is this expanding action which forms the bead f in the walls of the plug section. This completes the sealing of the filled can. It should be remembered that this sealing action is effected while the cans b are still moving around the stationary post 51.

At the end of the sealing action the cam 97 raises the cam slide 85 and the head supporting rod 87. This withdraws the end of the rod from engagement with the inner faces of the die members 101 and permits the endless spring 108 to again contract the die members 101, 102 as in Fig. 10. The sealing head D thereupon moves up into its original position which is above and spaced apart from the top of the sealed can. The can clamping arm 67 then moves away from the side of the can to the position shown in dot and dash lines in Fig. 8. This releases the sealed can which moves into the discharge instrumentalities.

The instrumentalities E include a continuously rotating discharge disc 115 (Figs. 2 and 3) which is mounted on a vertical shaft 116 (see also Fig. 1) carried in bearings 117 formed in the main frame 25. The disc is rotated by a gear 118 which is carried on the lower end of the shaft 116 and which meshes with a train of intermediate idler gears 119 in turn driven by the column driving gear 54. The idler gears are carried on studs 121 which are threaded into the main frame 25.

The sealed cans in mechanism C are delivered onto the discharge disc 115 by a guide bar 124 (Fig. 2) which extends into the space between the upper and lower members of the turret 46 and across the path of travel of the cans through the station containing the flap sealing mechanism C, the inner end of the guide bar terminating adjacent the column 48. The outer end of the bar connects with a curved guide rail 125 which is secured to the top of the main frame 25 and which extends around the periphery of the disc 115. An inner guide rail 126 also secured to the top of main frame 25 is spaced relative to and is parallel with the rail 125. One end of this rail connects with the guide rail 124 of the station wherein the flap sealing mechanism C is located.

The advancing sealed cans in mechanism C engage against the guide bar 124 and are thus removed from the pockets 45 of the turret 46 and are deflected toward the discharge disc 115. A projecting portion 128 (Fig. 2) of the turret, adjacent each pocket, pushes the removed can from its supporting pad 58 and places it on the discharge disc as the turret revolves past the guide bar. The rotating discharge disc carries the cans through a curved path of travel between the guide rails 125, 126 and then delivers them onto an endless inspection belt 131 (Figs. 1, 2 and 3).

The inspection belt 131 is disposed adjacent the disc 115 and in longitudinal alignment with the guide rails 125, 126, the top run of the belt being flush with the top of the disc. The belt is carried on a driving pulley 132 and an idler pulley 133. Driving pulley 132 is mounted on a short shaft 134 carried in a bearing 135 formed in the main frame 25 adjacent the disc 115. The shaft carries a bevel gear 136 which meshes with a similar bevel gear 137 mounted on the disc 115.

shaft 116 and secured by screws 138 to the bottom of the disc.

The idler pulley 133 is mounted on a short shaft 139 which is carried in bearings 141. These bearings are formed in an extension 142 of the main frame 25.

Cans delivered onto the inspection belt 131 are directed along a straight path of travel by spaced and parallel guide rails 143, 144 which 10 are connected to the ends of the curved guide rails 125, 126 and also to the frame extension 142. While the cans are on the belt they may be inspected for proper closing and sealing or other features as desired while they are advancing toward the end of the machine. At the end 15 of the belt the cans may be discharged to any suitable place of deposit.

It is thought that the invention and many of its attendant advantages will be understood from 20 the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for closing and sealing a fibre container having a closure element hingedly 30 mounted on the top wall thereof and adapted to be inserted into an opening in said wall of the container, the combination of mechanism for advancing a said container along a predetermined path of travel through the machine, means disposed in the path of the advancing container and above said closure element for engaging and inserting the closure element into the container opening, and means for expanding the inserted closure element within the container 35 opening and beneath the same for sealing the container during its further advancement.

2. In a machine for closing and sealing a fibre container having a closure element hingedly mounted on a wall thereof and adapted to be 45 inserted into an opening in a wall of said container, the combination of mechanism for advancing a plurality of said containers along a predetermined path of travel through the machine in a continuous procession, means disposed 50 in the path of the advancing containers and above said closure element for inserting the closure elements of said containers successively into the openings in the respective containers as they are being advanced, and means for expanding the 55 inserted closure elements within the container openings for sealing the containers during their further advancement.

3. In a machine for closing and sealing a fibre container having a closure element hingedly 60 mounted on the top wall thereof and adapted to be inserted into an opening in said wall of the container, the combination of means for advancing said container along a predetermined path of travel through the machine, devices disposed in 65 the path of the advancing container and above said closure element for inserting the latter into the container opening, a sealing head disposed above the path of travel of said container and actuated to travel in time with said container during a portion of its advancement, and die 70 members on said sealing head adapted to be moved into engagement with said inserted closure element for expanding the same within and beneath said opening and into container sealing

position while the head is traveling with the container.

4. In a machine for closing and sealing a fibre container having a closure element hingedly 5 mounted on a wall thereof and adapted to be inserted into an opening in a wall of said container, the combination of mechanism for advancing a said container along a predetermined path of travel through the machine, means disposed in the path of the advancing container and above said closure element for engaging and inserting the closure element into the container opening, means for expanding the inserted closure element within the container opening for sealing the container during its further advancement, and 10 clamping means moving with said container for holding the container firmly in position in said advancing mechanism during the expanding of said inserted closure element.

5. In a machine for closing and sealing a fibre 20 container having a closure element hingedly mounted on a wall thereof and adapted to be inserted into an opening in a wall of said container, the combination of mechanism for advancing a said container along a predetermined path 25 of travel through the machine, means disposed in the path of the advancing container and above said closure element for engaging and inserting the closure element into the container opening, means for expanding the inserted closure 30 element within the container opening for sealing the container during its further advancement, and discharge instrumentalities including a container inspecting station for discharging the sealed 35 container from the machine.

6. In a machine for closing and sealing a fibre container having a closure element hingedly mounted on the top wall thereof adapted to be inserted into an opening in said wall of the container, the combination of means including a 4 turret having container receiving pockets for advancing said container along a predetermined path of travel through the machine, means disposed in the path of the advancing container and above said closure element for engaging the same 4 and inserting it into the opening of said advancing container, a sealing head disposed above and traveling in time with a said advancing container in a pocket of said turret, yieldable means for supporting said container while in said turret 5 pocket, actuating devices for moving said sealing head down on said container for clamping the container firmly against the top of said turret adjacent the pocket and against the resistance of the yieldable supporting means, and die members 6 on said sealing head for expanding said inserted closure element within said opening and into container sealing position while the advancing container is so held.

7. In a machine for closing and sealing a fibre container having a hinged closure element attached to a wall of said container and adapted to be inserted into an opening in said wall, the combination of means for advancing a said container along a predetermined path of travel, means disposed above said path of travel for moving said closure element into inserted position in the opening of said container as the latter is advanced, and means for expanding the inserted closure element within the container opening for sealing the container as an incident to its further advancement.

JOHN M. HOTHERSALL.
AUGUST E. ALMGREN.
